UNITED STATES PATENT OFFICE.

ROBERT W. BRADLEY, OF DENVER, COLORADO.

FIRE-ESCAPE.

SPECIFICATION forming part of Letters Patent No. 293,707, dated February 19, 1884.

Application filed March 5, 1883. (No model.)

To all whom it may concern:

Be it known that I, ROBERT W. BRADLEY, a citizen of the United States, residing at Denver, in the county of Arapahoe and State of Colorado, have invented certain new and useful Improvements in Fire-Escapes; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention relates to improvements in fire-escapes, by which persons and merchandise can be removed from burning buildings without loss of life or injury to person or property, simple in construction, easily adjusted from high to lower stories, being light and strong, and so arranged that a child may descend from high buildings to the ground without injury. I attain these objects by means of the device illustrated by the accompanying drawings, forming a part of this specification.

Figure 1 is a direct front view. Fig. 2 is a side view. Fig. 3 is a section of the springs, showing attachment of springs. Fig. 4 is a representation of cuffs to be worn on the arms. Fig. 5 is a sectional view of the springs and cushion. Fig. 6 is an end view of the bottom.

A is a slide or chute, made of canvas or other flexible material, to the edges of which are secured wire, hemp, or other kind of ropes. One end of said ropes is provided with loops B B, adapted to attach to hooks C C, which are placed in the walls of buildings on either side of the windows, or through which a strong scantling may be passed, which is placed across the inside of the window, as shown in Fig. 1. The other end of the ropes is provided with loops B' B', adapted to receive hooks D D, which are attached to a cylindrical-shaped spring-receiver, E, the case of which is formed by the canvas, and by attaching a piece of canvas of like width and suitable length thereto. In either side of the spring-receiver are secured ropes d d, provided at one end with the hooks D D, and at the other end with loops F F. Through these loops passes a circular rope, H, to which is attached, by means of screws or nails f f, a circular board, I, having notches i, in which the ropes d d fit.

To the bottom I are attached springs k k k. To the opposite ends of the springs k k k is attached a circular board, I', having similar springs, k' k', to the other end of which a circular board, I², is secured. The board I² has a groove, l, extending around its entire circumference.

To the board I² is attached a cushion, which is covered with canvas, cloth, or leather, which extends downward to the board I', to which it is securely attached by nailing the covering to the edges of the board I', incasing the springs k' k'. A small cord, rope, or wire is drawn tight over the covering where it passes over the edge of the board I², compressing the covering into the groove in the circumference of the board I².

To the loops F F are attached ropes F' F', which are tied to posts G G. For the purpose of stretching out the lower end of the escape, a rope, L, is attached to the loops B B and extends toward the spring-receiver the entire length of the canvas. The canvas is provided with holes a a, for the purpose of receiving the hooks D D when it is desirable to shorten the escape.

The springs k and k' are attached to the boards I, I' and I² by passing the ends of the springs through the boards, and are clinched on the opposite side. Cuffs O, made of leather, provided with straps o', are worn on the elbows of heavy persons. The straps o' are held between the thumb and finger, the cuff fitting over the elbows, which enables the wearers to regulate the speed of their descent by pressing their elbows against the sides of the canvas. The circular boards I, I', and I², in order to secure lightness and strength, are made by gluing thin boards together, having their grains to run in opposite directions. To the canvas A are attached ropes p p, for the purpose of preventing the escape from being overturned by wind.

In order to operate my invention properly, the end of the canvas provided with the loops B B is attached to the hooks C C or to the scantling C'. The ropes F' F' are then securely fastened to posts G G, which are situated at a suitable distance from the building, which hold the lower end of the escape above the ground, and retain the escape in a sloping position, the lower end of the escape being a sufficient distance from the building to retain the escape at forty-five to sixty degrees. Persons or mer-

chandise placed in the upper end of the slide or chute slide down until they come in contact with a cushion arranged in connection with the spring-receiver, which compresses under the force of the body coming in contact with it, and relieves the shock, which would otherwise be severe, if not fatal. Persons can regulate the velocity of their descent by providing their arms with the cuffs O, and, as they descend, pressing their elbows against the sides of the slide or chute. The rope L provides another method for assisting persons to partially sustain their weight while descending by letting themselves down by their hands. Where high buildings are situated on narrow streets, the lower end of the fire-escape may be carried obliquely along the street, as shown in Fig. 2, or may be carried into windows or doors in houses on the opposite side of the street from that of the house from which it is desired to remove persons or property.

Having thus fully described my invention, what I claim as new, and desire to secure by Letters Patent, is—

1. In a fire-escape, a slide or chute, A, composed of canvas or other flexible material, having its edges strengthened by ropes provided with loops B B and loops B' B', and having its lower end formed into a cylindrical-shaped spring-receiver, E, the hooks D D, ropes d d, loops F F, stationary bottom I, springs k k k, partition-board I', springs k' k' k', and board I², having the cushion and cover attached, as specified and described. 25

2. The combination, with a fire-escape, of the slide or chute A and cylindrical spring-receiver E, the ropes H and F', and posts G, fully as set forth. 35

3. The combination, with a fire-escape, of the cuffs O, having straps o', for the purpose of protecting the elbows from injury while descending, fully as set forth and described. 40

In testimony whereof I affix my signature in presence of two witnesses.

ROBERT W. BRADLEY.
